(57) **CLAIM**

The ornamental design for a bedding with personal flaps as shown and described.

DESCRIPTION

FIG. 1 is a front perspective view of a bedding with personal flaps, according to an example embodiment;

FIG. 2 is a top view of the bedding with personal flaps shown in FIG. 1;

FIG. 3 is a bottom view of the bedding with personal flaps shown in FIG. 1;

FIG. 4 is a front view of the bedding with personal flaps shown in FIG. 1;

FIG. 5 is a back view of the bedding with personal flaps shown in FIG. 1;

FIG. 6 is a right side view of the bedding with personal flaps shown in FIG. 1;

FIG. 7 is a left side view of the bedding with personal flaps shown in FIG. 1;

FIG. 8 is a perspective view of the bedding with personal flaps shown in FIG. 1 in a first state of use;

FIG. 9 is a perspective view of the bedding with personal flaps shown in FIG. 1 in a second state of use;

FIG. 10 is a perspective view of the bedding with personal flaps shown in FIG. 1 in a third state of use;

FIG. 11 is a perspective view of the bedding with personal flaps shown in FIG. 1 in a fourth state of use;

FIG. 12 is a perspective view of the bedding with personal flaps shown in FIG. 1 in a fifth state of use; and,

FIG. 13 is a perspective view of the bedding with personal flaps with an arrangement of personal flaps that are a mirror image of the bedding with personal flaps shown in FIG. 1. Additional views of the mirror image of the bedding with personal flaps shown in FIG. 13 are not illustrated to avoid redundancy.

The broken lines in FIGS. 8-12 depicting the environment of two people and a mattress form no part of the claimed

(Continued)

design. The other broken lines in the drawings represent stitching which is not claimed.
